EXTRUSION FOR SASH MEMBERS OR THE LIKE

Harry M. Riegelman, 27012 Woodbrook Road,
Rolling Hills, Calif.

Continuation of design applications Ser. No. 79,786, May
4, 1964 and Ser. No. 76,181, Aug. 12, 1963. This ap-
plication Sept. 29, 1964, Ser. No. 82,211

Term of patent 14 years

(Cl. D13—6)

Fig. 2

Fig. 3

Fig. 4

Fig. 5

Fig. 6

FIGURE 1 is a partial perspective view of an extrusion for sash members and the like embodying my new design;

FIGURE 2 is a partial elevational view illustrating the rear surfaces of the extrusion shown in FIGURE 1;

FIGURE 3 is a plan view, as seen from either top or bottom, of the extrusion shown in FIGURE 2;

FIGURE 4 is a partial perspective view of another embodiment of my invention for an extrusion for sash members and the like;

FIGURE 5 is a partial perspective view illustrating the rear surfaces of the extrusion of FIGURE 4; and

FIGURE 6 is a plan view, as seen from either top or bottom, of the extrusion shown in FIGURE 4.

This is a continuation of application Serial Numbers D. 79,786, filed May 4, 1964, entitled Extrusion for Sash Members or the Like (which is a division of D. 76,186, filed August 12, 1963, for Extrusion) and D. 76,181, filed August 12, 1963, entitled Extrusion for Sash Members or the Like and now abandoned.

The center of the extrusion in the several views is broken away to indicate an article of indeterminate length.

I claim:

The ornamental design for an extrusion for sash members or the like, as shown in described.
